ATTORNEY.

UNITED STATES PATENT OFFICE

2,160,005

ELECTRICAL CHANGE-OVER

Chester Tappan, New York, N. Y., assignor to
 General Talking Pictures Corporation, New
 York, N. Y., a corporation of Delaware

Application September 10, 1935, Serial No. 39,924

2 Claims. (Cl. 179—100.3)

The present invention relates to improvements in electrical change-overs, that is, a simple and easily operated control change-over system for use in conjunction with sound-on-film theatrical projection apparatus, one object of the invention being the provision of means to control through a push-button, instead of the regular wheel operated fader, and which is more efficient in use and in operation and preventing any interruption in the transmission of sound when a change-over is made from one projector to the other.

Another object of this invention is the provision of means to produce an automatic dowsing of the light on one projector simultaneously with the opening of the aperture on the other projector.

Still another object of the invention is the provision of an apparatus to control the volume from either of two projecting machines or upon a non-synchronized apparatus or disc electrical pick-up, and to also change over the exciting lamp circuit from one sound head to the other or vice versa.

Still another object of this invention is the provision of means whereby the exciter lamp in the sound head which is not in service can be energized while the other machine is running, permitting the necessary focussing in the first machine so that the optical system can be tested and adjusted.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawing:—

Fig. 1 is a diagrammatic view of one electrical arrangement of the present change-over system.

Fig. 2 is a similar view of a modified circuit.

Fig. 3 is a diagram of an additional wiring that can be used with either one of the previous diagrams.

Referring to the drawing, and more particularly to Fig. 1 thereof, the numerals 1 and 2 designate the input from the left hand photoelectric cell amplifier and terminals 3 and 4 the right hand photoelectric amplifier output. A disc pick-up P is to be connected to the terminals 5 and 6 and is what is known in common parlance as a non-synchronized pick-up, so that musical and other records may be played over the amplifying

system as and when desired. A supply rectifier R is provided with the output terminals 7 and 8 while the terminals 9 and 10 indicate the conductors leading to the exciting lamps E—E' for the two sound heads (not shown). Beginning with the terminals 1—2, it will be noted that the terminal 2 has a conductor 2' connected to the output at terminal 11 while terminal 1 is connected through a conductor 1' to a pair of contacts of a switch 13 which is also utilized to transfer the input from the sound film to the sound disc terminal 5 and vice versa. From this point the switch 13 is connected to a pole of the double-pole-double-throw locking relay switch 14.

When switch 14 is in the up position the sound is led through to the input of the T-type attenuator 15 at which point the volume is controlled and thence to the other output terminal to complete the circuit. Similarly the terminal 3 of the right hand machine has the sound led through conductor 20 to a terminal 21 on the switch 14, and with the switch in the down position the sound in turn is led through conductor 22 to the attenuator 15, and hence through conductor 24 to the output terminal 12.

Similarly the positive 10-volt input is led through conductor 24 to the other side of the switch 14 and two terminals 9 and 10, this depending upon the position of the switch, whether it is up or down. Hence the lines 19 and 19' and the sound from each respective machine are operated simultaneously and each in turn is operated with its own respective machine.

The switch 14 constitutes a double coil relay or a two-position relay and the contacts are so arranged that they make before they break. This is desirable so as not to open either the sound or the exciting lamp circuit, and also as there is no unloading of either the amplifier or rectifier respectively. The coils in this relay are wound respectively for 10 volts direct current, and the push button 16 when operated will cause the switch 14 to move to its up-position and remain there after the push button is released, as this is a locking type relay. Therefore, if the push button 17 is operated the switch will move to its down position and in a like manner will remain locked, causing the transfer of the sound and the exciting lamp from one machine to the other.

It will be noted that a switch 18 is so connected that at such times as the left hand machine for instance is in operation, the right hand machine will have its exciting lamp energized for focussing purposes or vice versa. This switch is also provided with a neutral position so that it is com-

pletely out of circuit during normal operation of the machine. Thus it will be seen that a means is provided for emergencies due to possible failure of the relay or the parts of the circuit, and also for testing the respective exciter lamps and optical systems of one machine while the other machine is in projecting operation.

Although the attenuator 15 is here shown as connected in the circuit normally in the box within the projecting booth, it is to be noted that the same may be placed at any point wherever the conducting line or circuit may be placed, to be operated at a remote point or in the auditorium, so that a better quality of sound suitable to the capacity or every part of the auditorium may be obtained, or for that matter a duplicate attenuator placed in series with this attenuator 15 for remote adjustment may be employed.

It will be further noted that the pilot lamps 19 and 19' are placed in circuit for the convenience of the operator in order that at a glance at the front wall of the booth an immediate indication as to which machine is in operation, is given.

As it is preferred to use heater type tubes in the amplifiers used in conjunction with this change-over system, there is no difficulty with noise in the sound circuit when transferring from one exciter lamp to the other. If, however, this noise should occur, a small relay 21' is employed, the output of the amplifier being connected to the terminals 22' and 23' while the winding of this relay is connected across the actuating coil of the other relay. This auxiliary relay is a fast-acting relay so that it will actuate before relay 14, thus short-circuiting the output of the amplifier until such time as a complete transfer has been accomplished, the same becoming de-energized the instant the push-button is released, and permitting the voice currents to flow through the usual channels.

In the diagram shown in Fig. 2, the reference numerals which indicate similar parts to that in Fig. 1 are provided with a double-prime indication, the only difference being that instead of using one attenuator 15, "two attenuators 15" are employed. This has its advantages when sound is being transferred from one machine to the other and in which the level of one machine

is known as in some instances to be higher or lower than the output of the other machine. Thus, by anticipating this, the individual attenuator is regulated so as to compensate for this level during the transfer with the result that a uniform output from the main amplifier is maintained.

From the foregoing description, taken in connection with the drawing, it is evident that although the present arrangement shows circuits in more or less detail, it is evident however that changes in the precise embodiment may be made without departing from the spirit of the invention.

What is claimed is:

1. A combination with electrical mechanism for controlling two sound reproducing apparatus each of which has an exciter lamp, of an electrical network interposed, said apparatus including two push-button switches, one adjacent each apparatus, a main double acting electrically actuated switch, two electro magnets operable respectively from the push buttons to move the switch and hold the same in one of two directions, and an attenuator interposed in the circuit for controlling the quality of the sound originating in either apparatus, and a switch for each exciter lamp whereby either exciter lamp may be energized independently of the operation of its particular apparatus.

2. An electrical control mechanism, including in combination two sound reproducing apparatus each having an exciter lamp, two electrical networks, one interposed between each apparatus and including each a push button, a double acting electrically actuated switch common to both networks, one of the electrical members of which is adapted to be energized by one of the respective push buttons, two pilot lights, one for each apparatus, and one of which at a time is adapted to be energized when the switch is operated by its respective push button, and a T-type attenuator in said network for controlling the quality of sound originating in either apparatus and adapted to be connected in the network when said double acting switch is in either closed position.

CHESTER TAPPAN.
